UNITED STATES PATENT OFFICE

156,513

RUBBING MACHINE

Harold R. Johnson, Rockford, Ill.

Application April 15, 1949, Serial No. 1,998

Term of patent 14 years

(Cl. D9—2)

To all whom it may concern:

Be it known that I, Harold R. Johnson, a citizen of the United States, residing in Rockford, in the county of Winnebago and State of Illinois, have invented a new, original, and ornamental Design for a Rubbing Machine, of which the following is a specification, reference being had to the accompanying drawings, forming part thereof, in which:

Fig. 1 is a perspective view taken from a position at one end and to one side of a rubbing machine, embodying my new design;

Fig. 2 is an end elevational view of the rubbing machine of Fig. 1, and taken from the end opposite that shown in Fig. 1;

Fig. 3 is a side elevational view of the rubbing machine taken from the side opposite that shown in Fig. 1; and

Fig. 4 is a top plan view thereof.

I claim:

The ornamental design for a rubbing machine, substantially as shown.

HAROLD R. JOHNSON.
